UNITED STATES PATENT OFFICE.

FRANK W. KENNEDY, OF TRENTON, NEW JERSEY, ASSIGNOR TO DE LAVAL STEAM TURBINE COMPANY, OF NEW YORK, N. Y., A CORPORATION OF NEW JERSEY.

ELASTIC-FLUID TURBINE.

1,170,547.

Specification of Letters Patent.

Patented Feb. 8, 1916.

Application filed November 7, 1913. Serial No. 799,743.

To all whom it may concern:

Be it known that I, FRANK W. KENNEDY, a citizen of the United States of America, and a resident of Trenton, in the county of 5 Mercer and State of New Jersey, have invented certain new and useful Improvements in Elastic-Fluid Turbines, of which the following is a specification.

My invention relates to elastic fluid turbines, such a steam turbines, and particularly to means for limiting, to a predetermined maximum, the speed of such turbines.

My invention comprises a turbine rotor provided with fan blades arranged to interpose a progressively increasing resistance to rotation, as the speed of rotation rises.

Other features of my invention will be set forth hereafter.

My invention is particularly applicable 20 to small and relatively inexpensive fluid pressure turbines, in which simplicity and compactness is particularly required.

The object of my invention is to improve means for controlling the speed of elastic 25 fluid turbines, and to make the speed control device very simple and compact.

I will now proceed to describe my invention with reference to the accompanying drawing, in which—

30 Figure 1 shows a longitudinal axial section of a simple form of turbine embodying one form of my speed regulating device, and Fig. 2 shows an end view of the turbine.

In the drawings, 1 designates the turbine 35 casing, and 2 a removable cover for such casing, which cover carries the turbine nozzle 3.

4 designates the rotor or bucket-carrying disk of the turbine, 5 the rotor shaft and 6 40 a bracket having a bearing for such shaft.

7—7 designate the buckets of the turbine.

8—8 designate fan blades with which the rotor disk 4 is provided.

9—9 and 10 designate air inlet openings, 45 located near the center of the turbine casing, and 11 designates an exhaust opening for the escape of the exhaust motive fluid and of air.

The turbine herein described is particularly intended for operating a small high speed electric generator (not shown, but which will be connected to the rotor shaft in any suitable manner). The nozzles 3 of the turbine will be proportioned to give the

full load of the generator at a certain speed, 55 for instance 3600 revolutions per minute, at a predetermined steam pressure. The turbine is intended to operate without any automatic governor-valve mechanism. During the operation of the turbine the fan blades 60 8 draw air through the openings 9—9 and 10 into the turbine casing and force such air outward through the exhaust opening 11, with the exhaust motive fluid. As the speed of the rotor rises from zero, the fan blades 65 8 necessarily oppose an increasing resistance to the rotation of the rotor, but are so designed that such resistance is not detrimental up to the intended normal running speed (3600 revolutions per minute in the 70 instance assumed). If, while the turbine is in full operation, the load should be thrown off or greatly decreased (for example, suppose the load to be thrown off the generator driven by the turbine as previously stated), 75 the speed of rotation will necessarily increase to a certain extent, but the resistance offered by the fan blades will increase to a greater extent, and to such an extent that when a speed of say 4600 to 4800 revolutions 80 per minute has been reached an equilibrium between the power generated by the action of the steam blasts from the nozzles on the turbine blades, and the resistance to rotation offered by the fan blades 8, will be 85 reached. The fan blades are so designed that this equilibrium is reached well within the safe rotative speed of the turbine and of the machine driven thereby.

The fan blades not only limit the possible speed of the rotor, but also, by drawing air in through opening 10 around the shaft, avoid any occasion for use of a stuffing box or closely fitting bearing around this shaft to prevent escape of steam around the 90 shaft. In practice, the rotor disk employed is a cast disk, and the fan blades 8 are united to that disk by placing such blades in the mold in which the disk is cast, and casting the metal of the disk around said blades. 95 By this method of construction it is possible to produce a weld union between the blades 8 and the metal of the disk.

What I claim is:

1. In a fluid pressure turbine, the combination, with a rotor disk, of a fixed fan blade mounted thereon to rotate therewith, and of a size, and so disposed, as to inter-

pose effective progressively increasing resistance to motion of such rotor as the speed thereof rises.

2. In an elastic fluid turbine, the combination, with a rotor disk, of fixed fan blades secured to and projecting therefrom and arranged to travel in an air space surrounding such rotor, and of such size, and so disposed, as by their fan action to offer a progressively increasing effective resistance to motion of the rotor as the velocity of such rotor increases.

3. A turbine rotor disk provided with turbine buckets and also provided with fixed fan blades projecting from it and of such size and so arranged as to offer effective pro-

gressively increasing resistance to motion of such rotor as the velocity of such rotor increases.

4. A turbine rotor disk formed of cast metal and provided with buckets and also with cast-in fan blades, such fan blades arranged to offer progressively increasing resistance to motion of such rotor as the velocity of such rotor increases. 25

In testimony whereof I have signed this specification in the presence of two subscribing witnesses.

FRANK W. KENNEDY.
